BELT BUCKLE

William Geiser, 320 E. Greystone Ave., Monrovia, Calif.

Filed Oct. 31, 1960, Ser. No. 62,677

Term of patent 14 years

(Cl. D17—1)

FIG. 1.

FIG. 2.

FIG. 1 is a front elevation of the belt buckle, showing my new design; and

FIG. 2 is a top plan view of the belt buckle of FIG. 1.

I claim:

The ornamental design for a belt buckle, substantially as shown.
